FRANK C. WHITE, OF MERIDEN, CONNECTICUT, ASSIGNOR TO WILCOX & WHITE COMPANY, OF MERIDEN, CONNECTICUT, A CORPORATION OF CONNECTICUT.

AUTOPNEUMATIC MUSICAL INSTRUMENT.

No. 852,751.

Specification of Letters Patent.

Patented May 7, 1907.

Application filed March 18, 1906. Serial No. 305,748.

To all whom it may concern:

Be it known that I, FRANK C. WHITE, a citizen of the United States, residing at Meriden, county of New Haven, Connecticut, have invented certain new and useful Improvements in Autopneumatic Musical Instruments, of which the following is a full, clear, and exact description.

My invention relates to improvements in automatic piano players or pneumatic music playing instruments.

The object of the invention is to provide a tension regulating appliance which shall be compact, sensitive and quick in action. The construction of the regulator is likewise such that it may be automatically operated to change from high to low tension, or vice versa, quickly and effectively.

Other important advantages attained by my invention comprise a reduction in the number of parts employed, thereby saving in cost of construction, and increasing the durability and simplicity of the apparatus.

My invention also makes it possible to condense into much smaller space than has heretofore been possible a single apparatus which is at once a regulator and a tension modifier.

By my improvement the regulator may be effectively employed with such instruments as are provided with means for accentuating certain solo notes by attacking them under high tension while the accompaniment notes are operated under low tension. In this connection, my invention embraces a certain feature of improvement whereby in the playing of such selections, the accompaniment may be swelled or diminished at will to heighten the artistic effect.

It is immaterial where the regulator is placed, that is, whether it is placed between the wind chest and the exhaust, or whether it is on the other side of the wind chest from the exhaust, so as to act as an automatic choker, so called. In the drawings I shall illustrate and describe in detail one preferred form of my invention in the first mentioned location, but will diagrammatically show it in the second location.

In the accompanying drawings, Figure 1 is a vertical section of certain parts of a pneumatic piano or music playing instrument of well known construction, but fitted with my new improvement. Fig. 2 is a section on the

plane of the line 2—2 Fig. 1, the wind chest being broken away, the parts being in position to regulate and control the low tension. Fig. 3 is a similar sectional view, the parts being shown in position for high tension. Fig. 4 is an elevation of certain parts shown in Fig. 1, looking from left to right. Fig. 5 is a diagrammatic view.

It is unnecessary for me to describe in this application in detail the various parts of the action mechanism, since my invention is not dependent upon the specific form thereof, and since in the drawings I have chosen to illustrate a known action. To these known parts, therefore, I shall only refer briefly.

A represents what is commonly termed the wind chest, from which air is exhausted or withdrawn by means of a suitable bellows (not shown) in communication with the exhaust chamber B.

C is a power pneumatic for operating at the proper moment a key-striking lever or finger D.

E is the tracker. F represents a perforated sheet traveling over the perforated edge of said tracker.

The usual ducts G (indicated in dotted lines) lead to the pneumatics of the usual action valves indicated at H—H', through the operation of which air at atmosphere is admitted to the normally collapsed power pneumatic C to cause them to operate and 85 actuate the levers D.

In instruments of this character it is necessary, to attain the best results, to provide means for normally causing a uniformity of tension in the wind chest A. This I attain 90 by the following means. The exhaust chamber B is in communication with the wind chest A by what I may term a wind-way, the course of which is through a collapsible regulator bellows I. In the particular form 95 shown (referring to Fig. 2) J is a trunk, which may be connected at its upper end to the lower side of the wind chest A and at its lower end to the upper side of the exhaust chamber B. J' is a fixed partition in said trunk. K indicates a large open port in trunk J above the fixed partition J' and leading into the bellows I. L is a large port in the side of the trunk J below the fixed partition J'. Both of these ports communicate 105 with the interior of bellows I. Overstanding

the port L is a throttle M hinged at its lower edge, in the particular form shown. Through this throttle is a relatively smaller port N. O is a throttle carried by the throttle M and arranged to normally open and uncover port N. The ports N and L register. The exhaust chamber B is in direct communication with the ports L and N, and these are in direct communication (through the bellows 10 I) with the port K, and the latter is in direct communication with the wind chest A. P is a pin or shoulder on the inner side of the back board of the bellows I, and this bears against the throttle O so that as the bellows I collapses, the tendency will be to close the valve O and resist the freedom with which the air may be drawn through the port N.

From the foregoing it appears that at all 20 times the air will be exhausted from the wind chest A through the bellows I. It follows that the tension in the exhaust chamber B will determine the degree to which the bellows I is collapsed, and correspondingly, the degree 25 to which the bellows I is collapsed determines the freedom with which air may be withdrawn from the wind chest A. The flap valve O, therefore, determines and regulates, and holds in substantial uniformity the tension 30 in the wind chest A, under normal conditions. The degree of resistance in the bellows I determines the degree of the tension. The bellows I normally tends to open by the action of a spring Q, and in the preferred form 35 of construction this spring is mounted upon a movable support Q' pivoted so that it may be manually swung partially about its axis. The free end of spring Q suitably engages with the back board of the bellows I, for example, by engaging under a projection I'. An operating rod Q², provided with a finger 40 button or handle Q³, may be connected with the bracket or support Q', so that the angle of the spring Q may be shifted to control the degree of freedom with which the bellows I may be collapsed. From the foregoing it follows that when the finger button Q³ is depressed, the spring Q acts more powerfully 45 on the bellows and the tension of the exhaust within the wind chest A is increased, with the result that the operation of the power pneumatic C will be more vigorous.

R is a small power pneumatic, the function 50 of which is to operate the throttle M so as to open wide the port L, whenever desired, for the purpose of obtaining a high tension exhaust in the wind chest A. This operation may be effected in any desired manner, but is preferably brought about by the use of said pneumatic R, which normally stands open. In the tracker E there is a perforation communicating through duct S with valves T--T'. T is the primary valve and T' the secondary. When a perforation in the sheet F registers 55 with the last mentioned perforation in the

tracker, air rushes in and operates the primary valve T. This admits air at atmosphere in sufficient volume to the secondary valve T' to open the same quickly, and this opening of the secondary valve opens the 70 pneumatic R to the exhaust. This causes the quick collapse of the pneumatic R, and the latter being suitably connected, for example, by a rod R', with the throttle M, moves the same and opens wide the large or 75 high tension port L, (Fig. 3), thus making a much more free passage for the air from the wind chest A into the exhaust chamber B. This produces a high tension in chest A, and any power pneumatic that is operated at this 80 time will be operated with much vigor.

It will be understood that the air exhausted from the wind-chest always flows through a single passage, and its course is always through bellows I whether for high or low 85 tension. The port L is always utilized, whether the throttle M is up or down. When it is down it merely acts as a choker, the air still being free to flow through said port L by first passing through the relatively restricted 90 port N which registers therewith.

In the diagrammatic view, Fig. 5, I have conventionally shown the various parts. E is the tracker. E'--E' represent the usual note openings which are in communication 95 with the action valves for controlling the key-levers. E² represents a marginal opening which is in communication with the primary valve which controls the operation of the pneumatic R. In this figure I have 100 merely illustrated an arrangement diagrammatically, in which the regulator is conventionally illustrated at X, the wind chest at Y and the bellows or exhaust chamber at Z. In this arrangement air enters at X' directly 105 into the regulator, which is in communication with the wind chest Y, which in turn is in communication through an unpartitioned trunk J² with the exhaust chamber Z. This merely shows the regulator placed outside of 110 or beyond the wind chest, so as to act as a so called choker, rather than between the wind chest and the exhaust bellows.

What I claim is:

1. In an auto-pneumatic musical instrument, a tension regulator arranged to control the tension of the exhaust in the wind chest and comprising a collapsible bellows or the like, an admission port at one end, an outlet port at the other end, said ports communicating respectively with the wind chest and with the exhaust chamber, a movable throttle for one of said ports, and means for automatically opening the same, a port through said throttle of less cross-sectional 115 area than the area of the port over which said throttle stands, and a valve for said smaller port arranged to be operated by said bellows.

2. A regulator for auto-pneumatic musical 120

instruments, comprising a bellows, means for normally causing said bellows to expand, a wind-way passing through said bellows and leading from the wind chest to the exhaust chamber, a throttle in said wind-way, and means for operating the same, a restricted air passage through said throttle, and a valve for said restricted passage, the latter being operated by said bellows.

3. In an auto-pneumatic musical instrument, a wind-chest, a vacuum chamber, a trunk connecting the same, a fixed partition therein, a normally distended bellows, a communicating passage from one end of said trunk to the other through said bellows, a throttle within said bellows for said passage, a restricted passage therein, a valve carried by said throttle and arranged to control said restricted passage, means for operating the throttle, and independent means for operating the valve.

4. In an auto-pneumatic musical instrument, a wind chest, an exhaust chamber in communication therewith, a regulator to control the tension of the exhaust within the wind chest, said regulator comprising a bellows having an air admission port and an air exhaust port of relatively large proportions, a throttle for one of said ports, a restricted air passage in said valve, a throttle for said restricted passage, said valve being controlled by the bellows, and a power pneumatic for controlling the throttle, a valve for controlling said power pneumatic, a tracker, a perforation therein, a duct leading therefrom to said valve for controlling said power pneumatic, whereby when said tracker perforation is open to atmosphere said valve will be operated and the power pneumatic actuated to open said throttle and abruptly produce high tension in said wind chest.

5. In an auto-pneumatic musical instrument, a tracker, a tension regulating and ten-

sion changing device comprising a wind-way, a throttle therein, a power pneumatic controllable from the tracker for automatically opening said throttle to change from low tension to high tension, a contracted air passage through said throttle and a valve for said contracted passage, and a bellows in communication with the exhaust chamber of the instrument, said bellows automatically operating said valve to automatically regulate the low tension in the wind chest of said instrument.

6. In an auto-pneumatic musical instrument, a tracker, a tension regulating and tension changing device comprising a wind-way, a throttle therein, a power pneumatic controllable from the tracker for automatically opening said throttle to change from low tension to high tension, a contracted air passage through said throttle and a valve for said contracted passage, a bellows in communication with the exhaust chamber of the instrument, said bellows automatically operating said valve to automatically regulate the low tension in the wind chest of said instrument, and a manually controllable means to vary the freedom of operation of said bellows for manually varying the low tension.

7. In a regulator for auto-pneumatic musical instruments, comprising a bellows, means for normally causing said bellows to expand, a wind-way passing through said bellows and leading through the exhaust chamber, a throttle in said wind-way, and means for operating the same to abruptly open wide said wind-way, a restricted air passage through said throttle, and a valve for said restricted passage, the latter being operated by said bellows.

Corrections in Letters Patent No. 852,751.

It is hereby certified that in Letters Patent No. 852,751, granted May 7, 1907, upon the application of Frank C. White, of Meriden, Connecticut, for an improvement in "Autopneumatic Musical Instruments," errors appear in the printed specification requiring correction, as follows: In line 4, page 2, the word "throttle," first occurrence, should read *flap valve*; line 14, same page, the word "throttle" should read *flap valve*, and line 30, page 3, the words "valve" and "throttle" should be transposed; and that the said Letters Patent should be read with these corrections therein that the same may conform to the record of the case in the Patent Office.

Signed and sealed this 28th day of May, A. D., 1907.

[SEAL.]

E. B. MOORE,
Acting Commissioner of Patents.
